US0D1084540S

(12) **United States Design Patent** (10) **Patent No.:** **US D1,084,540 S**
(45) **Date of Patent:** **** Jul. 15, 2025**

(54) **PET FEEDER**

(71) Applicant: **ChunFeng Liang**, Dongguan (CN)

(72) Inventor: **ChunFeng Liang**, Dongguan (CN)

(**) Term: **15 Years**

(21) Appl. No.: **29/925,607**

(22) Filed: **Jan. 25, 2024**

(30) **Foreign Application Priority Data**

Sep. 5, 2023 (EM) 015033071-0001

(51) **LOC (15) Cl.** **30-03**

(52) **U.S. Cl.**

USPC **D30/132**

(58) **Field of Classification Search**

Primary Examiner — Susan Moon Lee

(57) **CLAIM**

The ornamental design for a pet feeder, as shown and described.

DESCRIPTION

FIG. 1 is a front, top perspective view of a pet feeder, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the pet feeder that form no part of the claimed design.

1 Claim, 8 Drawing Sheets
